TOOL FOR PREPARING TACOS OR THE LIKE

Gary A. Oedekerk, 6516 Glorywhite St.,
Lakewood, Calif. 90713

Filed Feb. 24, 1975, Ser. No. 552,273

Term of patent 14 years

Int. Cl. D7—04

U.S. Cl. D7—99

FIG. 1

FIG. 4

FIG. 5

FIG. 2

FIG. 3

FIG. 1 is a perspective view of a tool for preparing tacos or the like showing my new design;

FIG. 2 is a side elevational view taken from the side opposite that shown in FIG. 1, an intermediate portion of the handle stem has been omitted for convenience of illustration;

FIG. 3 is a top plan view thereof;

FIG. 4 is a front-elevational view thereof; and

FIG. 5 is a rear-elevational view thereof.

I claim:

The ornamental design for a tool for preparing tacos or the like, as shown and described.
